FIG. 7.

INVENTOR
David Guelbaum

UNITED STATES PATENT OFFICE.

DAVID GUELBAUM, OF SYRACUSE, NEW YORK.

WICKLESS OIL BURNER FOR LIGHTING AND HEATING.

1,421,215.

Specification of Letters Patent. Patented June 27, 1922.

Application filed February 26, 1921. Serial No. 448,060.

To all whom it may concern:

Be it known that I, DAVID GUELBAUM, a citizen of the United States, and a resident of Syracuse, in the county of Onondaga and 5 State of New York, have invented a certain new and useful Wickless Oil Burner for Lighting and Heating, of which the following is a specification.

This invention of a wickless oil-lighting 10 and heating appliance has for its object higher efficiency, cleanliness, safety and convenience in the use of kerosene and other oils for lighting and heating, and its design is based on the following properties of gases 15 and liquids:

1—The property of air, when passing in intimate contact with and over a liquid surface, to entrain and absorb minute particles of that liquid and to become more or less 20 saturated with same, at all temperatures.

2—In case of air and liquid fuel, such saturated air becomes a combustible gas, and will burn when ignited, as direct experiment shows.

25 3—Such a fuel-saturated stream of air, once started into circulation and ignited, will continue to circulate and burn by virtue of the capillary properties of air and liquid, similar to the common oil lamp, in which 30 the oil continues to circulate through the wick against gravitation and considerable friction, by virtue of its capillary property, aided by the natural draft created by the flame.

35 The amount of kerosene oil necessary to be diffused in a given volume of air for converting it into a perfect combustible mass developing maximum temperature, is about 1:10000 part of its volume.

40 This is at freezing temperature; for the average home temperature the ratio between the volumes of air and oil will be a little over 10000.

45 This shows that the oil diffused within the air, at perfect combustion, is extremely diluted, equaling the lightness of water vapor present in common air, and no extra draft will be required to circulate and lift the relatively very small quantity of entrained oil.

50 Therefore, in passing a continuous sheet stream of air impinging over a continually oil-wetted surface, the air will become a combustible mass, and once started in circulation and ignited will continue to circu- 55 late and burn, by virtue of the natural draft

created by its own flame, the air current taking the place of the common wick as an oil conveyor.

My invention comprises the above novel features, embodied in combinations and constructions, as hereinafter set forth and claimed and as shown on the accompanying drawings, in which like characters designate the same corresponding parts in all the views.

Fig. 1 shows a sectional elevation of the whole apparatus.

Fig. 2 is a fractional top view of the apparatus, with cover plate 19 removed.

Fig. 3 is a cross section of the apparatus 70 through the air inlets 11, on line *m m*.

Fig. 4 is a section through one of the radiating channels with its terminal connecting socket and supporting leg.

Fig. 5 is a horizontal section through the 75 same radiating channel and supporting leg, on line *n n* of Fig. 4.

Fig. 6 is a portion of the sectional elevation of Fig. 1, at 9 and 22, showing a slight 80 change in construction.

Fig. 7 shows an ensemble of the apparatus as applied to lighting.

As seen on the sectional elevation Fig. 1, the liquid fuel container (not shown on this view, but shown in ensemble on Fig. 7), 85 which may be of any form and placed anywhere, connects to the top of the inner pipe 1 of the modified mixing and proportioning valve shown, a patent application for which, in its original form, has been filed by the 90 present applicant Sept. 25, 1920, Ser. #412,736.

The pipe 1 is provided at its bottom with the longitudinal slots 42, through which the oil passes out of the pipe, spreading over the 95 divergent cone surface of the solid pipe extension 41 terminating in the hollow cylindrical portion 28 with the saw-teeth shaped ribs on its outer surface, as shown on Fig. 1.

The lower portion of the surface of the inner pipe extension 41, Fig. 1, in the passage 100 22, may be machined smooth or may be made file rough, in order to retain on it a permanent thin layer of oil, as may prove desirable.

Around the pipe 1 is slidingly fitted the sleeve 40, flanged and threaded on top and screwing in and out of the cylinder or casting 9. The bottom of the sleeve 40 is tapered both ways: its inner bevel is parallel to the 110

cone 41, its outer bevel is parallel to the beveled inside portion of the outer casing 9 at the passage 22.

By screwing in or out the sleeve 40, the narrow oil passage 43 and the wide air passage 22 are closed or opened as desired.

The light metal band 44 fastened to the top of cylinder 9 and passing over the flange 45 of the sleeve 40 and around the pipe 1, as shown on Figs. 1 and 2, serves as a stop for the sleeve 40 in screwing it out of the cylinder 9. The vertical portions of the band 44 and also the circumference of the flange 45 have graduation marks indicating the extent 15 of the opening of the oil and air passages 43 and 22.

The modifications of the mixing and proportioning valve shown, forming an integral part of the whole apparatus, as compared 20 with said original patent application #412,736 filed Sept. 25, 1920, consists in the following changes:

1st—The novel construction of the inner pipe 1 Fig. 1 and of the conformingly shaped 25 portion of the surrounding outer cylinder 9, namely: the lower part 28 of the inner pipe 1, as here shown, being made cylindrical instead of conical, with projecting saw-teeth shaped ribs on the outside, with its bottom 30 fastened to the bottom 46 of the pedestal 23, and having several square holes on its outer surface carrying the sockets or valves 31.

2d—The lower half of the surrounding outer cylinder 9, instead of being conical, is here made cylindrical all through on its outside, with a projecting curved portion and with saw-teeth shaped ribs on its inside, with its bottom screwed on to the top faucet 47 of the pedestal 23, and having its air inlet 40 openings 11 enclosed between the two flanges or rings 10 cast on its outside surface and clamped fast to the hollow piston 2 of the surrounding air-circulation starting device.

The projecting curved portion inside the outer cylinder 9 at the passage 22 may be made either solid, as shown on Fig. 1, or it may be reduced in size, or entirely omitted, and the clearance space filled up with some light absorbent porous fabric, as shown on 50 Fig. 6, according to the volatility of the oil used and its capillary affinity for diffusion with air.

The saw-teeth shaped ribs provided in the lower part of the passage 22 are for subjecting both streams—the air and the oil—to a zig-zag intermingling with each other.

The above mentioned air-circulation starting device consists of the hollow piston 2 with the attached cover 3, both having air inlet ports 12 and rubber flaps or rings 5 and 6, held in place by means of the light ferrules 8 passing through the hubs of the piston and cover 2 and 3 and flanged over.

These ferrules 8 are fitted to the outer cyl-

inder 9, and together with the hubs and rubber flaps are clamped fast to the flanges or rings 10 of the outer cylinder 9 by the piston 2 and its cover 3 bolted together.

Thus, the hollow piston 2 surrounding the air inlets 11 to the central mixing and proportioning valve forms one stationary body with the same.

The air inlets 11 and 12 are shown in plan on Fig. 3.

The stationary piston 2 is surrounded by 75 the movable cylinder 13 Fig. 1 with its two covers 14 and 15, both provided with the air inlet ports 16, the rubber flaps or rings 4 and 7 and the ferrules 17 and 18 slidingly fitted around the outer cylinder 9 and 80 flanged over the hubs of the covers and over the rubber flaps, as shown.

The air inlet ports 16 are shown in plan on Fig. 2, with the cover plate 19 removed. This cover plate 19 is supported by the ribs 85 20, Figs. 1 and 2, cast on top of the cover 14 and is held in place by the ferrules 18 flanged over it, the outside air having free access to the air inlet ports 16 through the circumferential clearance between the cover 90 plate 19 and the cover 14.

The movable outer cylinder 13 is held up in its upward position shown by the spring 21, located inside the movable cylinder 13 and pressing against the piston 2 at one end and 95 the cover 14 at its other end.

The action of the circulation-starter is as follows: Normally, when in working condition, with the combustion mixture ignited and air and oil circulating freely, the rubber flaps 4, 5, 6 and 7 are in a horizontal position as shown on Fig. 1, and the outside air passes freely through all the ports of the movable cylinder and those of the stationary piston into the interior of the mixing and proportioning valve.

When not in working condition, then, in order to start circulation just before ignition, the movable cylinder 13 of the circulation-starter is pressed down; the air in its 110 upper half becomes compressed, the rubber flaps 4 and 6 close the adjacent ports, the flaps 5 and 7 open fully, and the air from the upper half of the cylinder 13 is forced through the ports 11 into the interior of 115 the mixing and proportioning valve, while the lower half of cylinder 13 fills up with air.

Released, the cylinder 13 is lifted up by the spring 21; the air in its lower half becomes now compressed, the flaps 5 and 7 close the adjacent ports, the flaps 4 and 6 open fully, and the air from the lower half of cylinder 13 is forced through the ports 11 into the mixing and proportioning valve. 125

Thus, a few strokes of cylinder 13 forces a continuous current of air and of entrained oil with it through the zig-zagged passage

22 of the mixing valve up to the ultimate exit where it is ignited with a match and a normal draft established.

On either end of the piston 2, close to the 5 ferrules 8, are the rubber rings 0 to take up the shocks.

In its ensemble, as a complete working unit, the wickless oil-lighting and heating appliance comprises the central mixing valve 10 organically combined with the circulation-starter and with the pedestal.

The pedestal consists of the hollow base or frame 23 with the well or pocket 24 in the centre with the tapped faucet 47 on top.

15 From the well 24 several radial channels 25 branch out, terminating in the tapped sockets 26 on top of the legs 27, as shown on Figs. 1 and 4.

Into the top faucet 47 of the pedestal 23 20 is screwed the bottom end of the outer cylinder 9, while to the bottom 46 of the well is fastened the bottom end of the hollow cylindrical portion 28 of the inner pipe 1 of the mixing valve, by means of the two tap bolts 25 29 with the locking washer 30, as shown on Fig. 1.

The hollow cylindrical portion 28 has on its surface several square holes, just opposite the entrance to the channels 25, carrying 30 the sockets or valves 31, which are thus prevented from turning, but can move freely in or out of these square holes.

These sockets are tapped inside and hold the threaded ends of the rods 32, located 35 inside the channels 25. The other end of these rods pass through the legs 27 and have the hand knobs 33 fastened to them, as shown on Figs. 1, 4 and 5. 38 is a metal or rubber filler ring, closing up the outer 40 end of the channels 25.

To prevent the rods 32 from moving lengthwise they are provided with a circular notch, with the two set screws 34 abutting against it, as shown on Figs. 4 and 5.

45 Thus, by turning the handles 33 with the rods 32 to the right, the sockets 31 will be pulled out towards the rods, closing the channel entrances to the well 24, as is shown on the left side of Fig. 1; reversedly, by turning the handles 33 with the rods 32 to the left, the sockets 31 will be pushed away from the rods, and the channel entrances to the well 24 will be opened, as is shown on the right side of Fig. 1.

55 In this way the combustion mixture from the mixing valve can be supplied to any one of the terminal sockets 26, or cut off, as desired.

The bottom of the pedestal 23 is closed 60 up by the plate 35 fastened to the bottom flange of the pedestal, thus forming a large closed space communicating with the interior of the well 24 by the small holes 36 in the well bottom, as shown on Fig. 1.

65 Should any oil dripping occur while the

apparatus is not working and the oil passage 43 left unclosed, it will thus collect in that closed space and can be at any time drained off through the plugged up hole at 37, provided in one of the legs 27, as 70 shown on Fig. 1.

On Fig. 7, Sheet 2 of my wickless oil-lighting and heating appliance is shown in ensemble, as utilized for lighting purposes, with two of the terminal sockets connected to 75 closed high temperature lighting burners, described in my patent applications Ser. #439,453 and #442,432.

On the left is shown an auxiliary mixing and proportioning valve, described in my 80 previously mentioned patent application Ser. #412,736, introduced for the purpose of the final right proportioning of oil with air.

The other sockets may likewise simultaneously be connected to any other kind of 85 lighting or heating burner, and there may be as many connecting branches provided in the pedestal as desired.

The oil reservoir 39 is here shown attached direct to the top of the central mixing valve with a cock between; but it may 90 as well be located anywhere conveniently.

The advantages of my wickless oil-lighting and heating appliance over other methods of kerosene oil lighting and heating now existing are: 95

1—The air in my appliance automatically takes the place of the common wick as an oil-carrier to the burner.

2—Saving in oil consumption due to perfect combustion through exact mixing and proportioning of oil and air, giving a flame of maximum temperature, transmitting more heat and imparting higher incandescence to the mantle. 100

3—Relief from the wick and from the dirt and trouble associated with it.

4—Compactness and portability combined with perfect safety, due to the substantial construction of all parts, and to the separation of the burner proper from the oil container. 110

What I claim is:

1. A wickless oil-lighting and heating appliance, comprising an oil and air mixing valve, an air-circulation starter, a pedestal with conveying channels, means for closing and opening the entrances to said channels, substantially as and for the purposes specified. 115

2. A wickless oil-lighting and heating appliance, comprising an oil and air mixing valve having its inner oil-intake pipe and its outer air-inlet cylinder or casing fastened both to a common pedestal and provided 125 with an extension at the bottom of said inner pipe with projecting ribs and with holes for carrying sockets or valves and having outside flanges or rings on said outer cylinder enclosing its air intakes and provided with a 130

projecting curved portion and with ribs and grooves on its inside forming a zig-zag passage, an air-circulation starter, a pedestal with conveying channels, means for closing 5 and opening said channels, substantially as and for the purpose set forth.

3. A wickless oil-lighting and heating appliance, comprising an oil and air mixing valve, and an air-circulation starter having a 10 hollow piston fixed to and surrounding said mixing valve with air inlet ports in top and bottom and with hubs and clamping ferrules holding rubber flaps or valves and provided with shock absorbing rubber rings and having 15 an outer movable cylinder slidingly fitted to said piston and held up by a spring and with covers attached to top and bottom provided with air-inlet ports and hubs with clamping ferrules holding rubber flaps or 20 valves and with a protecting cover plate on top, a pedestal with conveying channels, means for opening and closing said channels, substantially as and for the purpose described.
- 25 4. A wickless oil-lighting and heating appliance, comprising an oil and air mixing valve, an air-circulation starter, and a pedes-

tal fastened to said mixing valve and having a hollow frame with a closed bottom attached to or cast on with a drain outlet and 30 with a well or pocket in the centre and with conveying channels having terminal connections at the outer end and entrances to said well or pocket at the inner end, means for opening or closing said entrances to the 35 channels, substantially as and for the purpose specified.

5. A wickless oil-lighting and heating appliance, comprising an oil and air mixing 40 valve, an air-circulation starter, a pedestal with conveying channels, and sockets or valves located in said mixing valve with rods passing through said channels and having one end screwed into said sockets and the other end notched and held by setscrews 45 and having handles attached for operating said rods and socket-valves, substantially as and for the purpose set forth.

In testimony whereof, I have hereunto signed my name, at Syracuse, in the county 50 of Onondaga, and State of New York, this 24th day of February, 1921.

DAVID GUELBAUM.
